US0D1103676S

(12) **United States Design Patent** (10) Patent No.: **US D1,103,676 S**
(45) Date of Patent: ** Dec. 2, 2025

(54) **AIR FRYER DRAWER**

(71) Applicant: **IB APPLIANCES US HOLDINGS LLC**, Downers Grove, IL (US)

(72) Inventors: **Youlin Xie**, Hangzhou (CN); **Pengfei Xu**, Hangzhou (CN)

(73) Assignee: **IB APPLIANCES US HOLDINGS, LLC**, Chicago, IL (US)

(**) Term: **15 Years**

(21) Appl. No.: **29/972,738**

(22) Filed: **Nov. 12, 2024**

Related U.S. Application Data

(63) Continuation of application No. 29/847,702, filed on Jul. 27, 2022, now Pat. No. Des. 1,056,605.

(57) **CLAIM**

The ornamental design for an air fryer drawer as shown and described.

DESCRIPTION

FIG. 1 is a perspective view of an air fryer drawer showing the new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines depict portions of the air fryer drawer that form no part of the claimed design.

1 Claim, 5 Drawing Sheets
